UNITED STATES PATENT OFFICE.

HARRY L. HUDSON, OF NEW YORK, N. Y.

SHEET-METAL BOX.

1,160,611.

Specification of Letters Patent. Patented Nov. 16, 1915.

Application filed December 3, 1912. Serial No. 734,712.

To all whom it may concern:

Be it known that I, HARRY L. HUDSON, a citizen of the United States, and resident of the borough of Brooklyn, in the city and State of New York, have invented a new and useful Improvement in Sheet-Metal Boxes, of which the following is a specification.

The object of my invention is to provide a sheet metal box in which the top member 10 may be interlocked to the body of the box against removal therefrom when once inserted in position.

This invention is particularly directed to that type of box which is filled with the material before the top member is applied thereto.

A practical embodiment of my invention is represented in the accompanying drawings, in which—

20 Figure 1 represents in side elevation the upper portion of a sheet metal box embodying my invention, Fig. 2 is a vertical central section through the same, and Fig. 3 is a view in side elevation of the separate top member.

25 The body portion of the box shown herein comprises a lower tubular member 1 and an upper tubular member 2. The upper edge of the lower member 1 is permanently united to the lower edge of the upper tubular member 2, as, for instance, by crimping the edges together.

30 The upper edge of the upper tubular member 2 is turned inwardly, as shown at 3, forming an inner annular shoulder at the mouth of the box. The separate top member 4 has a depending flange 5 which is fitted to be inserted within the mouth of the body portion of the box, the said flange fitting 35 closely the inwardly turned upper edge of the upper tubular member 2. This flange is provided with means for limiting the entry of the top member into the upper tubular member, which means, in the present instance, is shown as a peripheral external shoulder 6 arranged to engage the upper edge of the tubular member 2 when the top member is inserted into position.

35 The depending flange 5 of the top member 4 is further provided with means for interlocking the top member to the body portion of the box, which means is herein shown as one or more upwardly directed spring tongues 7 pressed outwardly from 40 the flange at the proper point to snap outwardly under the inwardly turned upper

edge 3 of the upper tubular member 2, when the top member 4 is inserted into its position.

From the above description it will be seen that a box is provided in which the separate top member may be interlocked with the body portion of the box after the box has been filled and that any attempt on the part of a person to remove the top member for unlawfully refilling the box or for any other purpose, will only serve to more firmly lock the top member to the body portion of the box, as the tongue or tongues 7 will be forced into the space between the inwardly turned flange 3 and the wall of the upper tubular member 2.

It is evident that slight changes may be resorted to in the form, construction and arrangement of the several parts without departing from the spirit and scope of my invention; hence I do not wish to limit myself strictly to the structure herein set forth, but

What I claim is:—

1. A sheet metal box comprising a tubular member having an inwardly turned upper edge and a separate top member having a depending flange fitted to enter the tubular member, said flange being provided with yielding means arranged to snap outwardly under the said inwardly turned upper edge of the tubular member for permanently locking the top member against withdrawal.

2. A sheet metal box comprising a tubular member having an inwardly turned upper edge and a separate top member having a depending flange fitted to enter the tubular member, said flange being provided with yielding means arranged to snap outwardly under the said inwardly turned upper edge of the tubular member for permanently locking the top member against withdrawal, the said flange being further provided with means arranged to engage the turned upper edge of the tubular member for limiting the entry of the top member.

3. A sheet metal box comprising a tubular member having an inwardly turned upper edge and a separate top member having a depending flange fitted to enter the tubular member, said flange being provided with yielding means arranged to snap outwardly under the said inwardly turned upper edge of the tubular member for permanently locking the top member against withdrawal, the said flange being further provided with a peripheral external shoulder arranged to en-

2
gage the turned upper edge of the tubular member for limiting the entry of the top member.

4. A sheet metal box comprising a tubular member having an inwardly turned upper edge and a separate top member having a depending flange fitted to enter the tubular member, said flange being provided with one or more upwardly directed spring tongues 10 pressed outwardly therefrom arranged to snap outwardly under the inwardly turned upper edge of said tubular member for permanently locking the top member against withdrawal.

15 5. A sheet metal box comprising a tubular member having an inwardly turned upper edge and a separate top member having a depending flange fitted to enter the tubular member, said flange being provided with 20 one or more upwardly directed spring tongues pressed outwardly therefrom arranged to snap outwardly under the in-

wardly turned upper edge of said tubular member for permanently locking the top member against withdrawal, the said flange 25 being further provided with a peripheral external shoulder arranged to engage the tubular member for limiting the entry of the top member.

6. A sheet metal box comprising a lower 30 tubular member, an upper tubular member permanently united thereto and having an inwardly turned upper edge and a separate top member permanently interlocked with the inwardly turned upper edge of the said 35 upper tubular member.

In testimony, that I claim the foregoing as my invention, I have signed my name in presence of two witnesses, this twentieth day of November 1912.

HARRY L. HUDSON.
